CONTROL MECHANISM

Harry F. Smith, Dayton, Ohio, assignor, by mesne assignments, to C. F. Kettering, Inc., Dayton, Ohio, a corporation of Delaware

Original application December 14, 1925, Serial No. 75,316, now Patent No. 1,823,382, September 15, 1931. Divided and this application November 3, 1927, Serial No. 230,881

5 Claims. (Cl. 175—375)

This invention relates to electrical control apparatus, and more particularly to switch mechanism.

One of the principal objects of the invention is to provide control mechanism responsive to varying pressure conditions to effect electrical control.

Still another object of the invention is to provide a switch mechanism which is non-arching during use.

Other features, objects and advantages of the invention will be apparent from the description and claims set out below, and the accompanying drawings.

15 In the drawings in which like characters of reference designate like parts throughout the several views thereof;

Fig. 1 is a vertical sectional view with parts in elevation, showing parts of the electrical control apparatus including the switch mechanism, as applied to the control of an electrically driven blower;

Fig. 2 is a vertical sectional view, at right-angles to Fig. 1, taken along the line 2—2 of Fig. 1;

Fig. 3 is a view diagrammatic in character of the blower and control mechanism, and comprising a wiring diagram of the control mechanism;

30 Fig. 4 is an enlarged somewhat diagrammatic elevational view showing one element of the control mechanism;

Fig. 5 is a vertical sectional view similar to Fig. 1 and showing a modification thereof;

35 Fig. 6 is a diagrammatic view similar to Fig. 3 but comprising the form of control mechanism shown in Fig. 5; and

Fig. 7 is a diagrammatic view of still another somewhat modified form of control.

40 For purposes of clearer description this invention is illustrated in connection with an electrically operated blower forming part of a system for generating, and delivering to a place of use, a combustible gas—such as producer gas. However, this is by way of illustration and not by way of necessary limitation. The switch mechanism of this invention is not at all so limited in its applicability, which is general. For example, 45 it is peculiarly well adapted for use with electric signs, because of its non-arching characteristics which leave it free from objectionable interference with radio reception.

This case is a division of the copending application of Harry F. Smith, Serial No. 75,316, filed

December 14, 1925, now Patent No. 1,823,382, issued September 15, 1931.

In the embodiment shown in the drawings, the blower or pump which is of the centrifugal type, is indicated at 25. This blower may be of any conventional character but very satisfactory results have been secured with a blower of the character generally shown in the drawings, which blower comprises a centrifugal fan or impeller having radial blades revolving in a volute casing. This blower is driven by a suitable operating or driving means illustrated as an electric motor 26, the blower being preferably in driving connection with the motor armature shaft; and associated therewith is control apparatus for governing the operation of this blower in a predetermined manner by control of the electric motor 26 driving this blower. As shown herein the blower 25 is connected to the generating chamber of a gas producer (not shown and which may be of any suitable construction) to draw a blast of air and moisture through the incandescent fuel bed within the generating chamber thereof to produce combustible gas, the blower delivering this combustible gas under pressure to a suitable delivery main. The generated combustible gas withdrawn from the producer is generally first cooled and then purified before it passes to the blower. As shown in Fig. 3, the inlet pipe 30 of the blower 25 is adapted to be connected to the purifier to receive the cooled and purified gas. The outlet 40 of the blower 25 is connected to a valve casing 51 which serves to control the delivery of the generated gas under pressure to either a vent pipe 42 or a delivery main 27, the latter leading to suitable work devices adapted to utilize the general gas, such as gas stoves, the burners of hot-water tanks, gas grates or other gas-utilizing apparatus.

The gas drawn from the purifier by the blower is forced from the blower casing through the outlet pipe 40, under any desired pressure, the pressure ordinarily in household use being only a few inches of water. Associated with this outlet pipe is suitable control valve mechanism by means of which it may be connected either to the delivery pipe 27 or to the vent pipe 42. Normally, when the plant is not in operation this valve mechanism is positioned to close the delivery line and to connect the outlet of the producer to the vent pipe. If a producer is operated continuously it will of course furnish combustible gas continuously but this tends to unnecessarily increase the cost of operation since when none of the work devices are in use the generated

110

gas would be wasted to atmosphere. Consequently the gas-generating system is adapted for what may be called "intermittent operation" in that the plant operates to generate gas, generally, only when gas is being used at a work device. Consequently if the plant has been standing idle,—"standing by" as it is called,—, it may be necessary to blast the fuel bed at a comparatively rapid rate for a brief period in order to bring it up to good gas-making condition. During starting of the plant, and during any such blowing-up period, the blower should be connected to a vent, as otherwise the products of the combustion during the blowing-up period would be forced into the house. Generally the gas producer or generator will be located in the basement of the house, or in some outhouse, while the work devices, such as the stove, the hot-water tank, the gas grates and the like, will be located in the living quarters of the house; so that the generator and the work devices may be located many feet apart. This invention not only provides control mechanism for the valve which connects the blower to the vent or to the house line, but in addition provides suitable control mechanism whereby operation of the gas-generating plant may be effected and controlled from a distant point, such for instance as a suitable control switch 45 located at the kitchen stove, or some similar place, such control being herein-after termed "remote control". In actual practice this switch is preferably attached directly to the manifold along the front of the stove, within which are located the various individual burner valves which control operation of the stove.

The outlet pipe 40, of the blower is attached to the inlet opening 50, of the valve casing 51, which casing is divided by an upstanding circular partition 52 into two compartments 53 and 54. The compartment 53 is connected through the inlet opening 50 to the outlet 40 of the blower, the compartment 54 being connected through the restricted opening 55 to the house delivery line 27. Inasmuch as the centrifugal blower delivers a definite maximum pressure at maximum operating speed the restricted opening 55 determines the maximum amount of gas which may pass into the house line during operation. Positioned within the compartment 54 is an upstanding hollow guide 58, which has slidably mounted therein the stem 59 of the disc valve 60, which valve is adapted in one position to seat upon the upper edge of the partition 52. The upper end of the casing 51 is open, and is attached, in gas-tight connection, to the lower end of the casing 65, which has an opening or passage 66 in the lower face thereof which opens into the open upper end of the casing 51. This opening 66 is provided with a downwardly extending flange or seat 67, adapted to cooperate with the upper face of the valve 60. This open casing 65 has a chamber 68 therein, which is connected to the passage 66. This chamber 68 is also connected by means of the passage 69, with the vent pipe 42. Positioned within the chamber 68 is an electromagnet designated generally by the numeral 75, which comprises generally a spool-shaped core 76, having a suitable winding 77 thereon, this magnet being adapted when energized to lift the valve 60 against the seat 67 to close connection between the inlet passage 50 and the vent pipe 42. When the magnet is not energized the weight of the valve 60 causes it to seat against the upper edge of the partition 52, thus opening connection between the inlet opening 50 and the

vent pipe 42 and closing connection between the inlet opening 50 and the house line 27. When the valve is held in uppermost position and against the seat 67 the inlet passage 50 is disconnected from vent and is connected to the house line 27, so that gas under suitable pressure is fed to that line. Within the passage 69 is a restricted opening 70 which functions with respect to the vent pipe just as does the opening 55 with respect to the house line.

For effecting the desired control of the gas generation the switch 45 may be made as a three-button switch, as shown diagrammatically in Fig. 3. This switch in practice is preferably of the press-button type, and each button opens or closes contact through a line switch. As shown diagrammatically in Fig. 3 there is a switch 80, which is used to close the proper circuits to cause the blower to start operating to blast the producer; a second switch 81 which is adapted to switch connection of the producer from the vent pipe to the house line after the blowing-up operation has proceeded long enough to properly condition the active zone of the fuel bed; and a switch 82 which stops operation of the blower and thereby shuts down the plant.

When it is desired to start the operation of the producer, presuming that it has been standing by, or that it is starting from cold and the fire is being freshly kindled therein from burning paper or the like placed in the ash-pit of the producer, the button 80 is pressed to close the switch associated therewith. One pole of this switch is connected by means of the conductor 84 to one terminal of the battery 85 or to any other source of electrical energy. If desired the electrical controls may be arranged to plug into the ordinary household electric line, with the use of suitable conventional transformers. It is only needed, therefore, that the switch 80 have one pole thereof attached to the source of electrical energy. The other pole is connected by means of the conductor 86, to one terminal or an electromagnet 87, the other terminal of which magnet is connected by means of the conductor 88 to the other pole of the battery 85, or other source of electrical energy. Closing the switch 80 energizes the magnet 87 and this in turn attracts the armature 90 which is pivotally mounted adjacent the end of the core 125 of the magnet 87. One end of this armature 90 is connected to one side 91 of the house-lighting line, the other end being provided with a contact 92 which cooperates with a corresponding contact 93, the contact 93 being connected by means of the conductor 94 with an electrode 95. This electrode is positioned within a suitable container 100, preferably of glass, which container comprises an inverted tube, closed at the top, within which the electrode 95 is mounted, and open at the bottom, the bottom extending down into a glass container 101, which is supported upon the top of the casing 65. This container holds a considerable quantity of electrolyte of any suitable character which is designated generally by the numeral 102, and the lower open end of the tube 100 extends to terminate within the electrolyte and below the end of the electrode 95. In practice it has been found that very satisfactory results have been obtained where this electrolyte consists of very dilute sulphuric acid. A thin layer 103 of paraffin oil or the like is preferably floated on top of the electrolyte to prevent evaporation. Also positioned with the container 101 is a second electrode 105. Both 150

these electrodes may be composed of any material which will stand up sufficiently under operation; but very satisfactory results have been secured with electrodes consisting of carbon. This second electrode extends down below the bottom of the inverted tubes 100 and into a layer of crushed or granulated carbon 106, which serves to greatly increase the surface area of this electrode and thereby serves to insure good electrical contact between the electrolyte 102 and the electrode 105. This electrode 105 is connected by means of the conductor 110 to one pole of the blower-operating motor 26, the other pole of which is connected by means of the conductor 111 to the other side of the house-lighting line. The two electrodes and the cooperating electrolyte therefore function as an auxiliary switch or contact member within the motor circuit, the contacts 92-93 constituting the main switch. Leading off from the top of the tube 100 is a passage 115 which opens into the inlet passage 50 of the valve casing. When the plant is not operating the valve 60 will be positioned upon the seat at the top of the partition 52, with open connection between the inlet 50 and the vent pipe 42. At the same time the pressures inside and outside of the tube 100 will be balanced since the inside of the tube is connected to atmosphere through the tube 115 and vent 42. So when the switch 80 is closed to start operation this will close the circuit through the magnet 87, which will swing the armature 90 to close the contacts 92 and 93. At this time both the electrode 95 and the electrode 105 will be immersed in the electrolyte and consequently the motor circuit will immediately be closed to cause operation of the blower. Because of the positioning of the valve 60 the gases fed from the blower will pass freely through the vent to atmosphere, the house line remaining closed off from the blower. So long as the switch 80 is held closed and the valve 60 remains seated on the partition 52 with the blower outlet connected to vent the blower will continue to operate to blow in the fuel bed.

Provided in the partition 52 is an orifice or passage 120 which connects the chamber 53 to the chamber 54, and beneath the valve 60 when that valve is seated on the partition 52. Connected to the space 54 within the valve casing is a passage 125, which leads into the bottom of a chamber 126 within the casing 127, supported above the container 101. The chamber 126 is provided with a flexible diaphragm 128, of leather or other suitable material, which is held in place by means of a suitable retaining ring 129 and has a weight 130 carried thereon, which weight tends to urge the diaphragm downwardly. Mounted upon the weight is an upwardly extending standard 131 which is connected to an arm 132 which is in turn attached to the pivoted armature 133, associated with the electromagnet 134. As pressure tends to build up in the chamber 126 below the diaphragm 128 the diaphragm is raised carrying the weight and arm 132 with it. The free end of the arm 132 has a latch member 135 associated therewith which moves behind the end of the armature 90, as the diaphragm moves upwardly, to latch that armature with the contacts 92 and 93 closed. As soon as this condition is realized the operator may remove his finger from the switch 80 as the motor circuit is then held closed so long as the pressure within the casing 127 is sufficiently great to hold the diaphragm up.

When it is desired to turn the gas from the vent 75 into the house line, the operator presses the button to close switch 81. This causes energizing of magnet 75, the current flowing from the battery 85 through the conductor 84, across the switch 81 along the conductor 138 connected to that switch and thence through the winding of the magnet, the direction of flow of the current being as desired. The magnet then lifts the valve 60 against the seat 67 to disconnect the blower from the vent pipe and connect it to the house line. The weight and proportions of the valve 60 are so arranged that when lifted against the seat 67 it will be held there by the normal pressure of the gas.

The blower at its normal rate of operation delivers gas at such a rate that there is a tendency for the pressure in the valve casing to continue to build up. As this pressure increases it acts through the passage 115 to affect the pressure existent in the tube 100 upon the top surface of the electrolyte and forces that electrolyte downwardly and out into the container 101. As the pressure continues to build up the electrolyte is forced downwardly below the lower end of electrode 95 to break the circuit. But due to the adhesion of the electrolyte to the lower end of the electrode as the level of the main body of the electrolyte falls materially below the end of the electrode that portion in contact with the electrode is retained in contact and its surface tension then causes a progressive diminution of the cross-section of the extended portion of electrolyte until it is "pinched off"—as shown diagrammatically in Fig. 4. As a result the current flow is not suddenly interrupted by quick breaking of contact with the contacts within arcing distance of each other; but is choked off as the resistance builds up due to the diminishing cross-section of the conducting portion of the electrolyte and consequently objectionable sparking evils and other evils normally attendant upon the breaking of a flowing current are not present as the current flow is finally interrupted at a flow which is substantially zero so far as objectionable results are concerned. This action is accentuated by forming the lower surface of the electrode substantially parallel with the surface of the electrolyte and of considerable extent; and further by adjusting the conductivity of the electrolyte so that the "necked down" or diminished portion below the electrode offers a rapidly increasing resistance which quickly cuts the current flow to unobjectionable proportions. When constructed as described and used with an electrolyte which wets the electrodes there will be a drop or film of the electrolyte left on the lower end of the electrode after break, and as the electrolyte rises again into contact with the drop the surface tension effects will cause substantially immediate spreading of the electrolyte into contact with the whole end of the electrode to give immediately a full, low resistance contact. However, the relative arrangement and proportioning of the parts is such that the pressure at this time is still sufficiently high to hold the latch 135 up to maintain the contacts 92 and 93 closed, and to hold the valve 60 against its seat 67. As the pressure in the delivery line rises, therefore, above a predetermined normal the current in the motor circuit is interrupted; and as the pressure falls the motor circuit will be again closed as soon as the electrolyte comes in contact with the electrode 95. Thus a continuously intermittent energizing of the operating motor will occur during use of the device, under normal gas-using operations the current to the motor and opera-

tion of the blower being normally interrupted a number of times a minute with the result that the effective pressure in the delivery main 27 is maintained substantially constant. In actual operation the blower itself generally does not cease movement as it is controlled during utilization of the gas, for the contact mechanism is responsive to slight pressure fluctuations and therefore the breaking of the motor circuit as the normal pressure is exceeded is so brief that inertia will cause continued rotation of the motor and blower parts. And the practical effect is to secure a substantially uniform gas pressure, with a very accurate and simple control for motors of conventional construction and characteristics.

When it is desired to terminate operation of the device for a period the button 82 is pressed to close that switch which completes a circuit through the conductors 140, 141 and 84, and battery 85 to energize the magnet 134. This swings the armature 133 to move the latch 135 into inoperative position and as the magnet 87 is at this time unenergized the spring 142 will swing the armature 90 to break the contact across the contact points 92 and 93 thus stopping the blower. Of course the operation may also be stopped by cutting off all the burners, or other work devices, when the increased line pressure will open the auxiliary contacts.

In Figs. 5 and 6 is shown a somewhat modified form of device. In the ordinary household use the gas plant may stand idle for considerable periods, overnight for example. Ofttimes the gas is used for heating the water in the hot-water system in which case there is a continuous load on the producer and the fuel bed is thus maintained in good gas-making condition so that it immediately responds to increased load to give any desired quantity of good gas within its capacity. But where the producer stands idle for any considerable period the ignited fuel may cool below incandescence so that it may be necessary to blow in the fuel bed afresh before good combustible gas in quantities may be secured. This may make necessary a wait of several minutes before suitable gas is secured, and would also make necessary igniting kindling material in the producer itself. In order that the fuel bed may be at all times maintained in suitable condition, even during considerable stand-by periods, means is provided whereby the blower is automatically operated at intervals to cause a short blowing in of the fuel bed to maintain it alight, this permitting remote control at all times. This means is shown in Figs. 5 and 6 in which the control mechanism is provided with a second electrode 200, which is similar to the electrode 95', but is of somewhat less length. In order to enclose these two electrodes a double tube 201 is provided which has two depending legs, one 100' which contains the electrode 95' and the other designated by the numeral 202 which houses the additional electrode 200. The upper ends of these two tubes are connected to the main body of the tube 201 by means of cement, or the like, as is shown in Fig. 5 of the drawing, for example. There is also positioned within the leg 200 of the main tube a second tube 203 which extends down below the normal stand-by level of the electrolyte and the interior of which is disconnected from the interior of the main body of the tube when its lower end is within the electrolyte. This tube 203 has a branch 204 extending to the outside of the main tube 201, within which is positioned a closure member having a predetermined orifice there-

through, the orifice member being designated by the numeral 205. This orifice member may be of any suitable character; but in practice a small piece of thermometer tubing functions very satisfactorily. The main part of the tube 201 is connected by means of passage 115' to the gas pressure within the valve casing as described above. During operation the tube 201 with its two depending legs 100' and 202 will be so filled with gas that the level of the electrolyte is at approximately the lower end of the electrode 95'. But when the plant is shut down or standing by the electrolyte rises within the legs 100' and 202 until it is at substantially the same level inside and outside thereof; except that as the electrolyte covers the lower end of tube 203 it traps gas therein and can rise in that tube only as the trapped gas escapes through the orifice in the member 205. And the effective area of that orifice is such that after a predetermined interval the gas will have escaped sufficiently to permit the electrolyte to move upwardly in the tube 203 to contact with the electrode 200. This electrode 200 is connected by means of a conductor 210 with the line 91' which is a circuit shunted around the main motor circuit contacts 92-93, this arrangement being such that as the electrolyte contacts with electrode 200 the motor is energized to start the blower to cause blowing in of the fuel bed. But the motor will run for only a brief period as its operation builds up pressure within the main tube 201, which breaks the contact. This blowing in period may be of such length as desired but ordinarily is just sufficient to liven up the fuel bed and keep it alight. The intervals between these periodic blastings will depend on the time necessary for the gas leakage from the tube 203 to permit closing of the by-pass circuit—and this depends on the size of the tube 203, the extent of necessary electrolyte rise therein, and the effective area of the orifice. In actual practice satisfactory results have been secured where these blastings occur at about five minute intervals; but the intervals between them may be regulated to suit operating conditions. Because of the normal stand-by positioning of the valve 60 the gas resulting from such periodical blasting will be discharged to vent.

In Fig. 7 is shown, diagrammatically, a modification which gives the same results as does the form of Figs. 5 and 6; but which is simpler in construction. In this figure a single large tube 225 is provided which is suitably supported from the cover 226, in gas-tight relation as is the case also in the other forms shown and described above. Extending down through the cover 226 and into the space within the tube 225 is a second tube 227, which is connected by means of the passage 115'' to the outlet of the blower, as described above. Mounted in the cover 226 and extending down different distances into the space between the two tubes 225 and 227 are two electrodes 95'' and 200'. Also mounted in the cover 226 is a leak tube 204' having an orifice member 205'. The operation and function of these several elements are the same as described above. In Fig. 7 the level of the electrolyte is shown as of immediately after stopping the blower and before any appreciable leakage of gas through the leak tube 204'. In Fig. 6 the level of the electrolyte is shown as of a time when the leakage through tube 204 has just permitted the electrolyte to contact with the electrode 200 to close the motor bypass circuit. In Figs. 1, 2, and 5 the level of the electrolyte is shown as of stand-by 150

period with the levels inside and outside the tube 100 the same.

5 While the forms of apparatus herein described constitute preferred embodiments of the invention, it is to be understood that the invention is not limited to these precise forms of apparatus, and that changes may be made in either without departing from the scope of the invention which is defined in the appended claims.

10 What is claimed is:

1. Electrolytic switch mechanism comprising a container, an electrolyte therein, an electrode normally immersed in said electrolyte, a second electrode extending into the container, a third electrode extending into the container and terminating above the lower end of said second electrode, a tube closed at its upper end surrounding said second and third electrodes and extending down into the liquid and having an opening below the liquid level, means for connecting the interior of said tube above the open portion thereof to a pressure source, and a restricted outlet providing a slow leak for the pressure space of said tube.

25 2. Electrolytic switch mechanism comprising a vessel adapted to contain an electrolyte, spaced contact members within said vessel normally immersed in the electrolyte, an inverted container closed at the top positioned about one of said contact members and having an open portion beneath the normal level of the electrolyte, and means for connecting the interior of said container above the open portion to a fluid pressure source, so that upon a predetermined increase in

30 pressure within the container above that existing within the said vessel on the exterior of the container, the electrolyte is depressed within said container below the end of said one contact member therein.

35 40 45 3. Electrolytic switch mechanism comprising a container, an electrolyte therein, an electrode normally immersed in said electrolyte, a second electrode extending into the container, the lower end of said second electrode terminating in a flat face, a tube closed at the top surrounding said second electrode and having an opening be-

low the normal level of the electrolyte and below the flat face of said electrode, and fluid pressure means effective upon the electrolyte within said tube to cause its level to rise and fall with its surface substantially parallel with the flat face 80 of the lower end of said electrode into and out of contact with said flat face, whereby the surface tension of the electrolyte cooperating with the flat face of said electrode produces a necking down effect as the level of the electrolyte moves 85 below the flat face of said second electrode.

4. Switch mechanism for an electrical circuit, comprising switch contacts in said electrical circuit, fluid pressure means communicating with a fluid pressure source for opening and closing said contacts within a predetermined pressure range, a second pair of switch contacts in said electrical circuit in series with said first mentioned switch contacts, a second fluid pressure means also communicating with said fluid pressure source for holding said second pair of switch contacts closed within the said predetermined pressure range of opening and closing of said first mentioned contacts, said second fluid pressure means operating at a different predetermined pressure range to release the holding of said second pair of switch contacts, and means for opening said second pair of switch contacts upon said release of the holding thereof.

5. Switch mechanism for an electrical circuit, 105 comprising a pair of cooperating switch contacts in said electrical circuit, fluid pressure means communicating with a fluid pressure source for opening and closing said contacts within a predetermined pressure range, a master control 110 switch for said circuit in series with said pair of switch contacts, a second pair of cooperating switch contacts in said electrical circuit shunted around said first mentioned pair and shunted around said master control switch, said second 115 pair of contacts being actuated by fluid pressure from said fluid pressure source but at a different predetermined pressure range to automatically close said circuit intermittently and for short periods when said master control switch is open. 120
